US00D578463S

(12) **United States Design Patent**
Tureaud et al.

(10) **Patent No.:** US D578,463 S
(45) **Date of Patent:** ** Oct. 14, 2008

(54) **UNDERWATER VEHICLE**

(75) Inventors: **Thomas F. Tureaud**, Fairfax, VA (US);
Daniel N. Dietz, Alexandria, VA (US);
Stacy J. Hills, Ashburn, VA (US);
Douglas E. Humphreys, Great Falls, VA (US);
Alexander V. Roup, Sterling, VA (US)

(73) Assignee: **Vehicle Control Technologies, Inc.**,
Reston, VA (US)

(**) Term: **14 Years**

(21) Appl. No.: **29/292,925**

(22) Filed: **Nov. 1, 2007**

(51) LOC (8) Cl. **12-06**

(52) U.S. Cl. **D12/308**; D12/317

(57) **CLAIM**

The ornamental design for an underwater vehicle, as shown and described.

DESCRIPTION

FIG. 1 is a top perspective view of an underwater vehicle in accordance with the present invention.

FIG. 2 is a rear perspective view of the underwater vehicle of FIG. 1;

FIG. 3 is a front elevation view of the underwater vehicle of FIG. 1;

FIG. 4 is a top plan view of the underwater vehicle of FIG. 1;

FIG. 5 is a bottom plan of the underwater vehicle of FIG. 1;

FIG. 6 is a rear elevation view of the underwater vehicle of FIG. 1; and,

FIG. 7 is a left elevation view of the underwater vehicle of FIG. 1, wherein the right elevation view of the underwater vehicle of FIG. 1 is a mirror image of FIG. 7.

The broken lines shown herein are for illustrative purposes and form no part of the claimed design.
